(57) **CLAIM**

I claim the ornamental design for a LED light bar frame for mounting one or more LED modules in a sign, substantially as shown and described.

DESCRIPTION

FIG. 1 is a perspective view of the LED light bar frame for mounting one or more LED modules in a sign in accordance with the present design.

FIG. 2 is a left side elevational view of the LED light bar frame for mounting one or more LED modules in a sign of FIG. 1.

FIG. 3 is a right side elevational view of the LED light bar frame for mounting one or more LED modules in a sign of FIG. 1.

FIG. 4 is a front elevational view of the LED light bar frame for mounting one or more LED modules in a sign of FIG. 1. FIG. 5 is a rear elevational view of the LED light bar frame for mounting one or more LED modules in a sign of FIG. 1. FIG. 6 is a top plan view of the LED light bar frame for mounting one or more LED modules in a sign of FIG. 1; and, FIG. 7 is a bottom plan view of the LED light bar frame for mounting one or more LED modules in a sign of FIG. 1n. The broken lines shown on the drawing views are for the purpose of illustrating environmental structure and form no part of the claimed design.
